UNITED STATES PATENT OFFICE.

WILLIAM HENRY PIKE, JR., OF ORANGE, NEW JERSEY, ASSIGNEE, BY MESNE ASSIGNMENTS, TO BURROUGHS ADDING MACHINE COMPANY, OF DETROIT, MICHIGAN, A CORPORATION OF MICHIGAN.

CALCULATING-MACHINE.

1,094,394.

Specification of Letters Patent. Patented Apr. 21, 1914.

Application filed August 5, 1904. Serial No. 219,667.

To all whom it may concern:

Be it known that I, WILLIAM H. PIKE, Jr., a citizen of the United States, and resident of Orange, Essex county, State of New Jersey, have invented certain new and useful Improvements in Calculating-Machines, of which the following is a specification.

This invention relates to improvements in adding and recording machines and the object of the invention is to provide simple and positive means for effecting the recording of totals and sub-totals in said machines.

The invention will be fully described in connection with the accompanying drawing, in which,

Figure 1 is a sectional view of so much of an adding and recording machine as is necessary to illustrate the present invention; Fig. 2 shows certain of the parts of Fig. 1 in a position which they assume in recording a sub-total; Fig. 3 shows certain parts of Fig. 2 in another position.

The present invention relates to an improvement in the class of machines represented in U. S. Letters Patent No. 504,963 to W. S. Burroughs. The invention is illustrated in connection with the machine shown and fully described in said Letters Patent and for a complete description of such machine reference is had to the patent, it being deemed only necessary to describe the novel features of the invention in this specification and such parts of the patented construction as immediately coöperate therewith. It is to be understood however that the invention is not limited to the particular machine illustrated in the patent specified but that it is applicable to other machines of the same class.

Referring to the drawing 800 indicates the main shaft of the machine from which most of the working parts are actuated.

C indicates a register frame which carries the usual registering mechanism. The register frame is pivoted to rock upon a shaft or pivot 900 and the register proper is operated by a series of pinions 916 actuated by racks 610. Upon a stud 942 is pivoted the three arm lever 917 which is drawn in one direction by a spring 982 and has an arm *g* with a V-shaped end engaging a V-shaped tooth on one of the side arms of the frame C. This construction serves to hold the frame

C yieldingly in either of its extreme positions when it is rocked on its pivot 900. The 55 rocking of the frame C serves to rock the lever 917 and this lever engages a rocking frame 920 carrying a series of teeth 926 which engage and lock the pinions 916 when they are withdrawn from the racks 610. 60 Upon the register frame C are two studs 958, 958^a which are adapted to be engaged by notches *w*², *w*³, upon opposite arms of a forked pitman 914. The pitman 914 is connected by a link 911 with a lever 227 fixed 65 on a rock shaft 204. On the lever 227 is a finger key 265. The key 265, link 911 and the forked end of the pitman 914 are normally held in their upper positions by a suitable spring 288. A pair of links 216 are 70 connected with the lever 227 and with an arm depending from the shaft 26^a and these links carry a rod 209 which is adapted to withdraw the retainers 415 from the racks 610 when the latter are to descend to turn 75 back the register wheels.

At each reciprocation of the main shaft 800 the pitman 914, when in the normal position, which it occupies in accumulating amounts is reciprocated. For this purpose 80 the pitman 914 is normally in engagement with an arm of the lever 913 which is rocked to and fro by connections from the main shaft 800. As shown the shaft 800 has an arm 813^a carrying a pawl 821 which engages 85 alternately pins 961, 961^a on extremities of the lever 913. The pawl 821 is normally held in line with the arm 813^a by a spring 883.

599 indicates a platen similar to a type- 90 writer platen and 618 a series of type co-operating therewith to print the numbers indicated by the register. The type 618 are carried by a series of levers 611 pivoted on a rod or shaft 600 connected with the 95 racks 610.

The construction and operation of the foregoing mechanism is exactly the same as that shown and described in the Burroughs patent, to which reference is made, and no 100 further description is deemed necessary hereon. In the machine described in said patent the key 265 is depressed to rock the lever 227 and held down during an entire cycle of operations when it is desired to 105 print a total on the platen and restore the

register to zero preparatory to beginning a new addition, as described in lines 94 to 123, page 5 of the patented specification. It is also possible in said machine to print a subtotal without restoring the register to zero by releasing the key 265 during the forward movement of the operating lever or during the first half of a cycle of operations effected by the main shaft 800, as described in the paragraph beginning line 124, page 5 of the patented specification. The peculiar manipulation of the total key 265 required for printing a sub-total in the Burroughs machine is difficult and troublesome and it distract^s the attention of the operator from the work in hand and thereby delays the operation of the machine. Furthermore, if the key is not released at the proper moment or interval in the series of movements the register will be restored to zero and the result of the work wiped out. It is also found that in power operated machines the operator cannot be relied upon to release the total key at the said proper moment to print a subtotal owing to the rapidity with which the machine is operated.

This invention consists in providing means in connection with a machine of the character described whereby the necessity for the operator to time his movements in respect to those of the machine is avoided, the machine being provided with parts which remain in position after adjustment during the entire cycle of operations to effect the required movements without any thought on the part of the operator.

In carrying out this invention, I make use of a part which I term a "controller" and which may be shifted to different positions, and which, when set in position preliminary to the movement of the racks to take a sub-total, prevents the lower arm of the pitman from operating on the lower stud to throw the pinions out of engagement with the racks. The preliminary adjustment of this controller may be effected in any suitable manner. I also provide means for varying at times the position of the pitman 914 so as to set the parts to secure a total and leave the machine clear.

The controller may consist of any part which will serve in one position to prevent the pitman from being operated from the shaft 800. As shown, the pitman derives its reciprocating motion from the arm 813^a on the shaft 800 through intermediate devices which may be adjusted by the controller so as to put said arm into or out of operative connection with the pitman as required.

The connection of the lever 913 with the pitman is through the medium of a stud 3 on the lever entering an "L" shaped slot in the pitman, a spring 5 tending to lift the pitman and keep the stud in the bottom of said slot, when the pitman will move longi-

tudinally with the oscillation of the lever at every movement of the arm 813^a. The parts may be operatively disconnected by means of the controller 2 shown as a blade, the lower end being above a stud 6 on the pitman, so that when the blade is depressed, the pitman is pushed down until the stud 3 is in the horizontal part of the slot 4 when the movement of the arm 813^a, while it will rock the lever 913, will not operate or impede movement to the pitman.

The preliminary adjustment of the controller, as shown, is suitably effected, as by depressing the same by means of a finger key, the frictional resistance of the blade of the controller in its bearings serving to hold it in place. For the purpose of withdrawing the rack retainers 415 when the sub-total key is operated, an elbow lever 7 is provided, this lever being pivoted to a frame 216 and having an arm in the path of a pin 8 on the stem of the controller 2. The side bars of the frame 216 are slotted at 9 so that the said frame may be operated without affecting the position of the lever 227 carrying the key 265 which I term the total key.

The operation of the sub-total devices is as follows: When the controller is in normal or raised position, as shown in Fig. 1, the rocker 913 reciprocates the pitman 914 during each movement of the main shaft and the operation of the machine is the same as fully described in the Burroughs patent. When the controller is shifted to the position shown in Fig. 2 and moves the rear end of the pitman down until the stud 3 stands in the horizontal branch of the slot 4, the rocking of the lever 913 then imparts no movement to the pitman 914. The effect of this is that the register wheels 916 remain in mesh with the racks 610 during the down and up movement of said racks. The downward movement of the racks restore the register to zero and the amount of the downward movement of each rack depends upon the initial position of the register wheel with which it engages. The downward movement of the racks therefore properly positions the type 618 for printing the sub-total. As the pinions remain in mesh with the racks, the upward or reverse movements of the racks restore the pinions to their initial position in which they indicate the sub-total. The regular operation of the machine may then be resumed until another sub-total or total is reached.

The total is secured from the adjustment of parts by the total key 265 which may be of any suitable character and arrangement. As shown, the devices are constructed and arranged to operate in taking a total and clearing the machine as in the aforesaid Burroughs patented structure and need not be here described, the key being set before

any operation of the machine to secure the total and requiring for this purpose no intermediate action by the operator.

With a machine equipped with such totalizing and sub-totalizing means, the operator is not required to time his movements to those of the machine to print a total or sub-total, the operations of the machine after the preliminary adjustments being the same as when registering a number. It will be understood that the term "key" is used herein to signify any device, such as a lever or slide, which may be adjusted to insure the desired operation of the parts of the machine. It will also be understood that the invention is susceptible of embodiment in other forms than those shown and described herein. The principal function of the sub-total devices is to disconnect the register frame operating from the action of the main shaft 800 while printing a sub-total and it will be evident that the mechanism between the main shaft and the register frame may be disconnected at some point other than that shown.

An important feature of difference between this invention and devices heretofore proposed for adapting a machine of the type illustrated to take a sub-total without manipulating the total key as described in Burroughs' Patent No. 504,963, is that the taking of a sub-total involves merely pressing a special key provided for that particular purpose and putting the machine through a single cycle of operation. The mechanisms heretofore proposed for permitting the taking of sub-totals without manipulating the "total" key of adding machines of the type referred to have necessitated movement of the total key as well as the sub-total key or causing the machine to have more than a single cycle of operation.

Having thus described the invention what is claimed as new is:

1. In a machine of the class described, the combination with register actuating racks, a register normally in engagement with said racks, a main shaft adapted to effect relative movement between the racks and register to actuate the latter, connections between the shaft and register for disengaging and reengaging the register and racks during the cycle of operations produced by each actuation of the shaft, and a total key controlling the action of said connections to effect totalizing movement of the register, of a second key adapted to vary the action of said connection to effect sub-totalizing movement of the register, independent of any movement of the total key.

2. In a machine of the class described, the combination with register actuating racks, a register normally in engagement with said racks, a main shaft adapted to

effect relative movement between the racks and register to actuate the latter, connections between the shaft and register for disengaging and reengaging the register and racks during the cycle of operations produced by each actuation of the shaft, and means controlling the action of said connections to effect totalizing movement of the register during the cycle of operations resulting from a single actuation of the main shaft, of a device adapted to be adjusted to render said connections inoperative to disengage the racks and register independent of any movement of the said total controlling means.

3. In a machine of the class described, the combination with register actuating racks, a register normally in engagement with said racks, a main shaft adapted to effect relative movement between the racks and register to actuate the latter, connections between the shaft and register for disengaging and reengaging the register and racks during the cycle of operations produced by each actuation of the shaft, and a total key controlling the action of said connections to effect totalizing movement of the register, of means adjustable to vary the action of said connections to effect sub-totalizing movement of the register without causing any movement of the total key.

4. In a machine of the class described, the combination with register actuating racks, a register normally in engagement with said racks, a main shaft adapted to effect relative movement between the racks and register to actuate the latter, connections between the shaft and register for disengaging and reengaging the register and racks during the cycle of operations produced by each actuation of the shaft, and a total key controlling the action of said connections to effect totalizing movement of the register, of a sub-total key adapted to disconnect the main shaft and register to cause the racks to effect sub-totalizing movement of the register without shifting the total key from its normal position.

5. In a machine of the class described, the combination with the register actuating racks, the register normally in engagement with said racks, a main shaft, connections between the main shaft and register for disengaging and reengaging the register and racks during the cycle of operations produced by each actuation of the shaft, including a pitman and a total key adapted to adjust the pitman to effect totalizing movement of the register, of a sub-total key adapted to render the pitman inoperative to disengage the racks and register and thereby effect sub-totalizing movement of the register independent of any movement of the total key.

6. In a machine of the class described, the

combination with the register and the register actuating racks, of the main shaft, connections between the main shaft and the register, including a pitman, having an angular slot therein, a movable pin engaging said slot, and a sub-total key arranged to adjust the pitman with respect to said pin, for the purpose set forth.

7. In a machine of the class described, the combination with the register and the register actuating racks, of the pitman 914 having an angular slot, the rocking lever 913 having a pin engaging said slot, and a sub-total key arranged to adjust the pitman relatively to said lever.

8. In a machine of the class described, the combination with the register and the register actuating racks, of the pitman 914, the rocking lever 913 arranged to normally actuate the pitman, a total key adapted to adjust the pitman to effect totalizing movement of the register, and a sub-total key adapted to disengage the lever and pitman,

independent of any movement of the total key.

9. In a machine of the class described, the combination with the register actuating racks and the register movable relative to said racks and normally in engagement therewith, of means for actuating the racks and register to effect additions and to either leave the accumulating devices set at zero or retain the accumulation, said means including two devices adapted to be manipulated wholly before the operation of the machine to effect such "total" or "sub-total" movement of the register and the movement of each being entirely independent of the other.

In testimony whereof I have signed my name to this specification in the presence of two subscribing witnesses.
